UNITED STATES PATENT OFFICE.

VICTOR E. HANNY, OF PHOENIX, ARIZONA.

DESIGN FOR A SHIRT.

43,763.

Specification for Design.

Patented Apr. 1, 1913.

Application filed August 22, 1912. Serial No. 716,542. Term of patent 14 years.

To all whom it may concern:

Be it known that I, VICTOR E. HANNY, a citizen of the United States, residing at Phoenix, in the county of Maricopa and State of Arizona, have invented a new, original, and ornamental Design for Shirts, of which the following is a specification, reference being had to the accompanying drawings, forming part thereof.

The figure is a plan view of the shirt showing my new design.

I claim:

The ornamental design for a shirt, as shown.

VICTOR E. HANNY.

Witnesses:

A. R. VOLK,
LEO BUCKLEY.
